(No Model.)

H. WILLIAMSON.

TOBACCO PIPE.

No. 599,433.

Patented Feb. 22, 1898.

UNITED STATES PATENT OFFICE.

HENRY WILLIAMSON, OF LONDON, ENGLAND.

TOBACCO-PIPE.

SPECIFICATION forming part of Letters Patent No. 599,433, dated February 22, 1898.

Application filed May 19, 1897. Serial No. 637,156. (No model.)

To all whom it may concern:

Be it known that I, HENRY WILLIAMSON, a subject of the Queen of Great Britain and Ireland, and a resident of 88 Jermyn street, St. 5 James, London, England, have invented certain new and useful Improvements in Tobacco-Pipes and Cigar and Cigarette Tubes, of which the following is a specification.

My invention relates to tobacco-pipes and 10 cigar and cigarette tubes or holders, and has for its object to provide means compactly combined with the smoking appliance, so as practically to form a part thereof, whereby it may be kept continually clean, wholesome, 15 and uninjurious to the smoker and whereby also deposits and moisture may be readily removed whenever required with ease and efficiency.

My invention consists in the provision and 20 combination, with the pipe or tube, of a wound reel, ball, or coil or a loosely-woven fabric or other conveniently-packed store of continuous flexible absorbent filament—such as worsted, woolen cord, string, or the like—of 25 the same or varying thickness and in the nature of an absorber, or it may be a wire with interrupted absorbing material or occasional brushes fixed to it. Such store of cleaning material (hereinafter for convenience called 30 “cord”) is so arranged upon or within or in connection with the pipe or tube as to be isolated from the smoke-channel and so kept clean. A length of it, however, is led from the store and always lies in the smoke-channel, 35 having its free end led thereout in such manner that when required to clean the pipe or tube the whole of the fouled and impregnated length can always be easily drawn out, severed, and thrown away, leaving a 40 clean length in its place. There are several ways in which the store of cord may be combined with the pipe or tube, and I will now describe, in reference to the drawings, two preferred arrangements; but it is to be understood I lay claim to the broad combination 45 hereinafter specified.

Figure 1 is a sectional elevation of a pipe made in three parts, shown separated. Fig. 2 is a section of a cigar - holder alternative to the tobacco-bowl. Fig. 3 is a sectional plan of the pipe with the three parts separated. Fig. 4 is a sectional elevation of

same pipe put together. Fig. 5 is an elevation of the reel partly wound with cord, and Fig. 6 is an end view thereof. Fig. 7 is an inverted plan of a simpler form of pipe and storage arrangement. Fig. 8 is a detail sectional view illustrating the manner of supporting the cord-holder on the bowl portion of the pipe.

Similar letters and numerals refer to similar parts in all the figures.

The appliance shown in Figs. 1 to 6 is in three parts—the bowl 1, or, alternatively, the cigar-holder 1^a, the stem or body 2, and the 65 mouthpiece 3. The smoke-channel of the bowl or holder is enlarged at *a* to receive the reduced end *b* of the stem 2, which consists of a hollow cylinder or body of wood, vulcanite, or the like closed at its front end and having a central smoke-channel extending through a tube *b*^X, projecting for a suitable distance at *b*'. The mouthpiece 3 has the usual smoke-channel *B*^X, in part adapted to receive the said end *b*', and its exterior circumference fits into the open end of the stem 70 75 2. It has also a passage *D*, bored or formed longitudinally through the solid material and isolated from the smoke-channel *B*^X, and at the mouth end a curved recess *d* is formed 80 between passage *D* and channel *B*^X.

R is the store-reel, consisting of a hollow cylinder or cone provided with end flanges *r'* *r*² and adapted to fit loosely, so as to rotate upon the tube *b*^X. Upon the reel the cord *C* 85 is wound, and the free end passes over the reel-flange *r*², thence through the isolated passage *D* and recess *d*, and, following the arrows, along the smoke-channel *B*^X, from which it may leave 90 between cavity *a* and reduced end *b*, whereat a knife-edged cutting device of any suitable kind may be applied; or in a pipe the cord *C* may be continued along the smoke-channel and leave the bowl at a hole *a'*, fitted with a plug *a*², in which case the pipe might be in 95 one, two, or more parts and arranged as shown dotted in Figs. 1 and 3. By this construction a length of the absorbent cord *C* constantly lies in the smoke-channels *B* *B*^X and takes up all moisture and impurities, and when it is foul or saturated it is only necessary to separate the parts 1 and 2 or remove the plug *a*², take the cord *C* by its clean extremity, draw same forward, thereby unwind- 100

ing clean cord from the reel R until all the foul portion is withdrawn, then break off same, or if a cutter is used it will be severed on putting together the parts 1 and 2. A shallow groove may, if desired, be provided in the wall of the cavity a or in the circumference of the part b for the cord to lie in, or for the same purpose a separate hole may be made in the part b with or without a plug-stopper, so that the cord may be withdrawn without separating the parts 1 and 2.

In the simpler form illustrated in Fig. 7 the pipe is made in two parts 1 and 3, and the cord C is led from the store ball or coil R along passage D and channel B^X, leaving the pipe either between the parts a and b or at a plugged hole a' below the bowl 1, as above described. The ball or coil R is shown as enclosed in a receptacle R', formed in the material of the bowl beneath same and provided with a lid or screw-cover, the cord issuing from a small hole r and being led to an open end d' of the passage D.

Having now described my invention, what I claim as new, and desire to secure by Letters Patent, is—

1. In combination with a pipe, a cord-holder carried thereby, and a cord extending from said holder and lying in the smoke tube or channel, substantially as described.
2. In combination with a pipe, a cord-holder

carried thereby, and a cord extending from said holder and lying in the smoke tube or channel, said pipe having an exit-opening for the cord, substantially as described. 35

3. In combination, the bowl with its stem separable therefrom, the cord-holder, and the cord extending therefrom out through the joint between the stem and bowl, substantially as described. 40

4. In combination with a pipe, cigar or cigarette tube, a holder for an absorbent cord carried thereby and a passage or channel D for directing the cord into the smoke tube or channel, substantially as described. 45

5. In combination with a pipe or the like a separable tube for smokers' use, a holder for an absorbent cord carried by the pipe, said cord being directed through the smoke tube or channel, substantially as described. 50

6. In combination the bowl, the tube separable therefrom, the cord-holder carried by the tube and the passage extending through the tube for directing the cord through the smoke tube or channel, substantially as described.

In witness whereof I have hereunto set my hand in presence of two witnesses.

HENRY WILLIAMSON.

Witnesses:

ALFRED B. CAMPBELL,
FRED C. HARRIS.
